UNITED STATES PATENT OFFICE.

FRANK JONES, OF SALT LAKE CITY, UTAH.

BEET-LOADING MACHINE.

1,356,529.

Specification of Letters Patent. Patented Oct. 26, 1920.

Application filed August 8, 1919. Serial No. 316,092.

To all whom it may concern:

Be it known that I, FRANK JONES, a citizen of the United States, residing at Salt Lake City, in the county of Salt Lake and State of Utah, have invented certain new and useful Improvements in Beet-Loading Machines, of which the following is a specification.

My invention relates to certain new and useful improvements in material handling machines and particularly in machines which are designed for the special purpose of reclaiming beets from stock piles; and the invention consists of the parts and the constructions, arrangements and combinations of parts which I will hereinafter describe and point out in the appended claims.

In the accompanying drawings forming part of this specification and in which similar reference characters indicate like parts in the several views:

Figure 1 is a side elevation of a beet loading machine embodying my invention.

Fig. 2 is a top plan view of the same, showing the troughing belt omitted and the upper part of the conveying and screening belt broken away.

Fig. 3 is an end view of the upper portion of the discharge end of the machine.

While the invention I am about to describe is designed primarily for the reclaiming of beets from stock piles and screening out the dirt and foreign matter and finally depositing the beets in a clean condition into a suitable conveyance, or transferring said beets to a desired point of deposit, the operation being a continuous one, I desire it understood that I do not limit my invention to this particular use as the machine will be found of value in other fields and wherever it is desired to remove loose material from a pile or dump and screen the same of foreign or objectionable matter and then transport the cleaned material to another point for final deposit.

A leading object of my invention is to construct a single machine of the traction or self-propelled type, operated by a suitable engine or motor, and which machine shall embody means for propelling said machine and driving the various mechanisms thereof; means for entering the pile of

beets, or other material, to remove a portion of the same; conveying means for receiving beets or material directly from the pile, said last-named means having the capacity of separating from the beets the associated dirt or foreign matter during the conveyance of the beets, or material; and a second conveying means situated to directly receive the cleaned beets, or material and convey the same to a conveyance, or place of deposit.

In carrying out my invention I construct the forward end of the machine with a suitable frame, *e*, of angle-iron or other material and of such dimensions as I may wish, to suit the particular work for which the machine is designed, said frame being set at a suitable incline and having solid vertical castings, or standards, *g*, at the sides intermediate of the ends and which are securely bolted to the frame, said castings or standards being formed with bearings, *h*, *i*, *j*, and *k* as shown in Fig. 1, the bearings *i*, being for the reception of the journals of a transverse shaft *m* carrying bearing wheels or rollers, *n*, upon which the inclined forward end of the machine is supported. Suitable fingers *a*, arranged horizontally side-by-side in spaced relation are carried at the lower front end of the machine; the rear ends of these fingers are slightly inclined and are bolted or otherwise secured to the bearing block, *h*, on the castings or brackets, *g*, and from this point the series of spaced fingers project forwardly and are substantially horizontally disposed and are designed to be advanced or pushed into the lower portion of the pile of beets or material to be handled so as to lift and remove a portion of the same.

The exterior fingers may be flanked by guards or shoes, *r*, *r'* formed by front extensions of the sides of the frame and which may serve as dividers of the pile and prevent the beets rolling over the sides of the series of fingers, said guards or shoes being bolted or otherwise secured to the bearing block, *h*, and to a bracket, *h'* at the lower front end of the frame, *e*. To prevent the beets rolling under the bearing wheels of the succeeding traction part of the machine, I extend along the side of the front inclined

conveyer portion adjacent the ground, a suitable guard, g' , the opposite portions of which are secured respectively to the frame e , and the bearing for the shaft of the 5 front supporting wheels A of the succeeding traction portion of the machine.

Within the frame e are mounted the shafts or rollers d, d' , which support a series of suitable endless conveying belts which 10 preferably are of the link-belt type; *i. e.* the belt comprises a series of detachable links with special attachments—which convey and elevate the beets, or material to another conveyer disposed adjacent the delivery end of the series of belts. The chain-belts are spaced apart to form intermediate openings, say about one inch wide, which permit the dirt or foreign matter usually found associated with the beets, to fall 15 through and separate from the beets. Thus the series of chain-belts constitute an endless-carrier screen-belt the function of which is to directly receive the dirty beets from the separating fingers, a and to advance and elevate the beets and at the same time cause the screening and separation of associated dirt, whereby the beets will be delivered in a clean condition at the upper end of the conveyer. The central portions 20 of the chain-belts are supported on rollers, k' , on shafts mounted in the bearings k , of the castings g .

On the upper shaft d' of the conveyer is a sprocket wheel, N^2 from which a chain f , 25 leads to a sprocket wheel, G^2 on a transverse shaft E^2 mounted in bearings secured to the main frame, B^3 of the traction portion of the machine, as shown in Fig. 1. This portion of the machine is coupled or connected to the before-described front portion by means of a draw-bar or coupling links, P , one end of which is pivotally connected to the main frame, B^3 while the opposite or forward end is pivotally mounted 35 in the bearings, j , in the castings or brackets, g , of the inclined forward portion of the machine. By this arrangement, as the main frame is propelled forward or backward the same motion is transmitted to the 40 forward coupled portion of the machine, in which the aforesaid chain conveyer is mounted.

Referring to Fig. 1, the upper end of the frame e , is attached to side chains, t , or 45 like flexible connections which lead downwardly and rearwardly to a winding drum or shaft, u , mounted on the main frame, B^3 , of the traction portion of the machine and provided with a hand-lever, v , by which 50 the frame, e , may be vertically tilted about its bearing wheels or rollers, n, n' , to raise and lower the front fingers, a , relatively to the ground; a suitable pawl-and-ratchet mechanism 3 may be employed to secure the 55 shaft or winding drum and thereby hold the

frame e and its associated parts in their adjusted positions.

The traction portion of the machine has its front bearing wheels loosely mounted on the transverse shaft, B , and these wheels, 70 preferably are supplied with a central circumferential rib or flange which tends to guide the machine in a definite direction.

At the rear end of the main frame, B^3 is mounted a horizontal transverse winding 75 drum or shaft, D , from which extends forwardly the chains, C , or like connections, and which pass over the idler pulleys, 4 , and have their forward ends attached to the front axle or shaft B , said winding drum or 80 shaft, D , having a worm wheel, E , engaged by a worm, E , on a vertical shaft carrying at its top a hand wheel, F . This or an equivalent arrangement is utilized for steering the machine since by the operation of 85 the hand wheel, F , the front axle, B , may be turned to the right or left, as desired.

The main frame, B^3 , of the traction portion of the machine may be of any desired construction and arrangement and is designed to suitably support the frame E^3 of the trough conveyer, the two frames being 90 suitably rigidly connected and the frame E^3 supporting the trough conveyer and, also, serving as a cantilever in supporting a discharge chute, H , and the head pulley, L^2 , of said conveyer. The trough conveyer may otherwise be of the well known construction with its tail pulley, G , troughing rollers, G' , and the usual adjuncts of a conveyer of this 100 type. At the right-hand side of the machine a guard, F^3 is used, attached to the main frame just in advance of the main wheels, for clearing the track of beets.

In operation, the beets dug from the pile 105 by the fingers, a , are elevated and screened and the clean beets are delivered into a chute, 5 , at the delivery end of the chain conveyer and are thence directed onto the receiving end of the troughing conveyer and 110 by said conveyer the clean beets are elevated and delivered into the chute, H , which guides them into a conveyance.

Power necessary to propel the machine and operate the several mechanisms thereof is derived from an engine, I , of appropriate type having a gear, J , which is designed to drive a gear, K , on the shaft L , having a sprocket wheel, Z , which latter drives the chain, M , sprocket wheel, N , and 115 shaft, O , said shaft carrying the friction wheels, P, Q , which revolve with the shaft. A yoke, R , attached to the friction wheels, P, Q , is actuated by a lever, S , whereby when this lever is moved to one side the 120 friction wheel, P , is in contact with a friction wheel, T , thus driving the latter in one direction. By moving the lever, S , to the opposite side, the friction wheel, P , is removed from driving engagement with the 125 130

- friction wheel, T, and the friction wheel, Q, is brought into operative engagement with the friction wheel, T, causing the latter to rotate in the opposite direction.
- 5 The friction wheel, T, is on the shaft, U, to which is attached a worm, V, which drives a worm wheel, W, on the drive axle, X, to which the main supporting or traction wheels, Y, are secured.
- 10 The main frame, B², is supported on the drive axle, X, and the machine is, by the mechanism described, caused to move either forward or backward depending on which friction wheel is in engagement with the 15 friction wheel T.
- At the end of the shaft, O, is a clutch, A², which revolves therewith and is actuated by a lever, B², which when moved to one side connects the clutch with a pinion C², 20 fixed on the shaft and meshing with a gear wheel, D², on the shaft, E², which carries the sprocket wheels, F², G², which transmit motion to the conveyers, as will be readily understood by those skilled in the art.
- 25 The full operation will be understood from the foregoing description. Briefly, the machine is driven to the point where the pile of beets is located, and the fingers are pushed into the pile and a portion of 30 the beets lifted and fall onto the chain conveyer and are elevated by the latter and at the same time separated from the associated dirt; the clean beets are then delivered to the troughing conveyer and finally are dis- 35 charged by the chute, H, into the desired conveyance.
- With a machine such as I have described, I am able to reclaim beets, or the like, from a stock pile and screen and load the same 40 by one continuous operation. The machine being of the tractor type, can be propelled either around the pile and take a swath or it can be propelled forward taking a swath of beets and then be propelled backward 45 empty ready for a second swath. The machine can also be propelled ahead a few inches at a time causing the beets to fall upon the chain conveyer which screens and elevates them to the trough - conveyer.
- 50 While this description refers particularly to handling beets, it will be apparent that other loose material may be handled in a like manner without departing from the spirit of the invention.
- 55 Having thus described my invention what I claim as new and desire to secure by Letters Patent is:
1. A machine of the tractor type for reclaiming beets from a stock pile, screening 60 and loading them by one continuous operation, said machine having, in combination, a tiltable screening and conveying mechanism at the front extremity provided with a series of spaced fingers at one end adapted 65 to be pushed into said pile, a conveyer suc- ceeding and directly connecting with the delivery end of said screening and conveying mechanism, a motor, and driving connections between the motor and the machine and said conveyers, said screening and conveying mechanism having a part adapted to fulcrum against the ground to change the inclination of said mechanism. 70
2. A machine of the tractor type for reclaiming beets from a stock pile, screening 75 and loading them by one continuous operation, said machine having, in combination, a series of spaced fingers at one end adapted to be pushed into said pile, a combined conveying and screening mechanism succeeding 80 said fingers and receiving the beets therefrom, a conveyer succeeding and directly connecting with the delivery end of said elevating and screening mechanism, a motor, driving connections between the motor and the machine and said conveyers, said conveying and screening mechanism comprising a frame coupled to the front extremity of the machine and having spaced endless belts mounted therein and having an intermediate portion adapted as a ground fulcrum about which the frame is tiltable. 85
3. A machine of the tractor type for reclaiming beets from a stock pile, screening 90 and loading them by one continuous operation, said machine having, in combination, a series of spaced fingers at one end adapted to be pushed into said pile, a combined conveying and screening mechanism succeeding 95 said fingers and receiving the beets therefrom, a conveyer succeeding and directly connecting with the delivery end of said elevating and screening mechanism, a motor, driving connections between the motor and the machine and said conveyers, said conveying and screening mechanism comprising a frame at the front extremity of the machine, spaced endless belts mounted in said frame, a ground support for the frame intermediate of the ends thereof, and 100 means for tilting the frame about said support to raise or lower the fingers relatively to the ground. 110
4. A machine of the tractor type for reclaiming beets from a stock pile, screening 115 and loading them by one continuous operation, said machine having, in combination, a series of spaced fingers at one end adapted to be pushed into said pile, a combined conveying and screening mechanism succeeding 120 said fingers and receiving the beets therefrom, a conveyer succeeding and directly connecting with the delivery end of said elevating and screening mechanism, a motor, driving connections between the motor and the machine and said conveyers, said conveying and screening mechanism comprising an upwardly inclined frame, 125 spaced endless belts mounted in said frame, standards on the sides of the frame, inter- 130

- mediate of the ends thereof, having a ground-roller support, and a bearing member extending between said standards and to which the rear ends of the fingers are secured.
5. A machine of the tractor type for reclaiming beets from a stock pile, screening and loading them by one continuous operation, said machine having, in combination, a series of spaced fingers at one end adapted to be pushed into said pile, a combined conveying and screening mechanism succeeding said fingers and receiving the beets therefrom a conveyer succeeding and directly connecting with the delivery end of said elevating and screening mechanism, a motor, driving connections between the motor and the machine and said conveyers, said conveying and screening mechanism comprising an upwardly inclined frame, spaced endless belts mounted in said frame, standards on the sides of the frame intermediate of the ends thereof having a ground-roller support, a bearing member extending between said standards and to which the rear ends of the fingers are secured, and means for varying the inclination of said frame and the conveying and screening mechanism.
- 30 6. In a machine of the character described, the combination with a tractor having complementary power and transmission mechanisms, of a frame having ground engaging side standards intermediate of its length and spaced endless carriers for conveying and screening material received thereon, spaced fingers fixed to said frame and projecting in advance of the receiving end of said carriers and adapted to be pushed into a pile of material to be handled, and to deliver removed portions thereof onto said carriers, rearwardly extending coupling means between the front portion of the tractor and said standards, a conveyer on the tractor connecting with the delivery end of said carriers, and connections from the power mechanism of the tractor for operating said carriers and conveyer.
7. In a machine of the character described, the combination with a tractor having complementary power and transmission mechanisms, of a frame having ground engaging standards intermediate of its length and spaced endless carriers for conveying and screening material received thereon, spaced fingers fixed to said frame and projecting in advance of the receiving end of said carriers and adapted to be pushed into a pile of material to be handled, and to deliver removed portions thereof onto said carriers, rearwardly extending coupling means between the front portion of the tractor and said standards, a conveyer on the tractor connecting with the delivery end of said carriers, connections from the power mechanism of the tractor for operating said carriers and conveyer.
- 35 8. In a machine of the character described, the combination with a tractor having complementary power and transmission mechanisms, of a frame having spaced endless carriers for conveying and screening material received thereon, spaced fingers fixed to said frame and projecting in advance of the receiving end of said carriers and adapted to be pushed into a pile of material to be handled, and to deliver removed portions thereof onto said carriers, coupling means between the tractor and said frame, a conveyer on the tractor connecting with the delivery end of said carriers, connections from the power mechanism of the tractor for operating said carriers and conveyer, adjusting means on the tractor connecting with said frame and tilting the latter about a horizontal axis to adjust the said fingers relatively to the ground, said adjusting means comprising a winding drum, means for operating said drum, and a flexible connection from the drum to said frame.
- 90 9. The combination with a wheeled tractor having complementary driving and transmission mechanisms, of a wheeled conveyer frame, coupling means between the frame and tractor, a series of endless conveyer belts arranged side by side in said frame and spaced transversely apart to permit dirt and foreign matter to separate from the beets while the latter are being conveyed, a series of spaced fingers secured to the frame adjacent the ground and extending beyond the receiving end of said belts and adapted to be pushed into a pile of beets and to direct beets onto the belts, and guards adjacent the outermost fingers of the series for preventing the beets rolling off the fingers.
- 95 10. The combination with a wheeled tractor having complementary driving and transmission mechanisms, of an inclined conveyer frame coupled in line with the tractor and having means for removing screening and transporting the material to be handled, and a guard extending from the conveyer frame across the space between the same and the tractor, to prevent material rolling under the wheels of said tractor.
11. The combination with a wheeled tractor having complementary driving and transmission mechanisms, of an inclined conveyer frame coupled in line with the tractor and having means for removing screening and transporting the material to be handled, a guard extending from the conveyer frame across the space between the same and the tractor, to prevent material

rolling under the wheels of said tractor, and a guard attached to the side of the tractor to clear the track of material.

12. The combination with a conveyer having means for removing material from a pile and screening and elevating said material, of a tractor coupled in line with the conveyer and having a conveyer belt and

carrying frame therefor said frame being of a cantaliver type supported from the main frame of the tractor, and a discharge chute at the end of the cantaliver frame and supported thereby.

In testimony whereof I affix my signature.

FRANK JONES.
